UNITED STATES PATENT OFFICE

2,482,870

PREFABRICATED CESSPOOL STRUCTURE

Louis P. Price, Honolulu, Territory of Hawaii

Application November 12, 1947, Serial No. 785,463

2 Claims. (Cl. 182—2)

1

This invention relates to cesspools or other such subterranean chambers used for the collection of fluid waste.

An object of the invention is to provide a cesspool or the like comprising preformed sectional units which may be arranged as desired to form a structure of any desired capacity and which may be erected in but a small fraction of the time employed in the construction of a cesspool by the usually-followed procedure.

Another object of the invention is to provide a cesspool structure which permits erection operations to be carried out from operating positions entirely above the surface of the ground thereby protecting the workmen engaged in the work of installation from the many hazards which sub-surface excavations entail and releasing them from the usual duties of planking and shoring the sides of the excavation to insure against cave-ins.

A further object of the invention is to provide a sectional cesspool structure which when buried in the ground is fully capable of withstanding crushing strains such as may be imposed thereon by vehicles of reasonable weight passing thereover.

Still another object of the invention is to provide a cesspool designed to facilitate outward flow of its fluid contents as the level of the latter descends due to natural seepage of the fluid into the surrounding soil.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawings and description may be adopted within the scope of the invention as set forth in the claims.

Referring to the drawing:

Figure 1 is a view partly in side elevation and partly in vertical section showing a cesspool constructed in accordance with the principles of my invention.

Figure 2 is a perspective view of one section of the cesspool casing.

Figure 3 is a perspective view of one of the intersectional keys.

In many rural and suburban areas, cesspools or septic tanks, as they are often referred to, are commonly used to dispose of excreta and waste materials. Such cesspools are usually constructed by excavating in the ground at a suit-

2

able location a pit of the desired size and depth, usually about eight feet in diameter and extending downwardly beyond ten or twelve feet until soil of suitable porous and fluid-conducting characteristics is reached. In the pit is then constructed an axially vertical tubular casing of natural stone, pressed brick or, in many instances, wood, the casing being made purposely of a porous nature so as to permit liquid waste which may subsequently enter the cesspool through the sewer pipe leading thereinto to gradually seep into the surrounding soil. A suitable cover is then placed on the casing and the excavation, exteriorly of the casing and cover is back-filled with earth. It often occurs that the soil in which the excavation is made is of a sandy or loosely packed nature which results in the excavators being placed in constant jeopardy of being trapped or buried by sidewall cave-ins. Cesspools constructed in such ground also often collapse due to the radial pressure of the shifty surrounding soil against the loosely piled stones or bricks comprising the casing.

The cesspool structure of my invention overcomes to a great extent the production hazards set forth above, shortens the usual time-consuming procedure of installation and produces a structure capable of withstanding all normal stresses tending to crush component parts of the structure or to cause relative offsetting of some parts relative to others thereof. I provide a component unit of the structure as shown in Figure 2 comprising a preferably cast concrete casing 4, of circular or other desirable cross-sectional shape, having a bore 6 extending axially therethrough and provided with relatively parallel top and bottom surfaces 7 and 8 respectively. I have found it best to employ a casing of at least six feet internal diameter with a wall thickness measuring approximately four inches, suitable reinforcement in the form of wire mesh 9 or the like being molded into the wall to give the section adequate strength against fracture or crumbling during the operations of handling, shipping or installation. I provide casing sections in axial lengths of one, two, three and six feet which when combined in any desired grouping can be made to produce, to the nearest foot, a unit casing of any length. The four foot section, however, is considered as the standard and the drawing and description herein are based on such a unit.

The bottom end face 8 of the casing section is preferably made as a continuous unobstructed plane face but the opposite end face 7 has therein

two or more, but preferably four, key notches 11 and at least one waste line opening 12 which may also be a notch slightly larger than the key notches. The arrangement is such that when two casing sections are brought into axially abutting relation, the bottom end surface 8 of the upper section overlies and closes the notches 11 and 12 thus converting the latter to apertures spaced peripherally around the casing.

Each casing section is also provided with a plurality of peripherally spaced vent passages 13 extending through the wall thereof and vertically inclined to lie at substantially an angle of forty-five degrees with respect to the axis of the section, the uppermost open end of each passage intersecting the bore surface of the section and being positioned closer to the upper face 7 than the lower end of the passage. I have found the best proportions for the openings forming the passages 13 to be a horizontal width of about nine inches and a vertical height of about two and one-half inches. Also I have found that efficient operation calls for the provision of horizontal rows of passages spaced vertically preferably at two-foot centers and with each row containing about sixteen passages spaced equidistantly around the casing section.

Installation of the cesspool is effected by excavating an earth bore 14, as shown in Figure 1, having a diameter at least one foot in excess of that of the casing and extending to a depth of one and one-half feet in excess of the total required depth of the cesspool casing. Such excavation may be conveniently carried out by means of a clamshell bucket operated from above ground level by an automotive crane or other suitable operating mechanism. In many instances earth will be encountered which is sufficiently compacted to be self-sustaining while the excavation is being made but where the soil is crumbly it may be necessary to sink a sheet metal dam sleeve into the earth as the excavation progresses so as to prevent caving in of the sides of the bore. In some instances also, the excavation may extend downwardly below the level of the sub-surface water table in which case the use of the dam sleeve is imperative. After the excavation has been completed and the bottom thereof has been substantially levelled, the first casing section is lowered into place and substantially centered with the earth bore, the notched end 7 of the casing of course being uppermost. After the aforesaid first section has been properly set, centering keys 16, which are shown in Figure 3, are placed in the key notches 11. Each key 16 comprises a substantially H-shaped cast concrete body having a rectangular bar portion 17 at the opposite ends of which are provided integral head portions 18 having wings 19 extending oppositely beyond the top and bottom surfaces of the bar portion. The transverse cross-sectional form of the bar portion is made to conform with the vertical cross-sectional area of a key notch 11 so that the bar portion will fit freely into and fill the key notch. The length of the bar portion is slightly in excess of the casing wall thickness so that the wings 19 extend upwardly and downwardly along the inner and outer wall surfaces of two casing sections which may be placed in superposed coaxial alignment. It will be noted that the inner surface 21 of each wing is upwardly and outwardly inclined with respect to its junction with the top or bottom surface, as the case may be, of the bar portion so as to insure tight wedging of the key against the bottom of the key notch and against

the confronting bottom surface 8 of the superposed casing section which is next placed on the previously set section as shown in Figure 1. The upwardly opening gaps of the placed keys 5 between the upper wings 19 thereof cooperate to form a pocket into which the overlying casing section may be moved so as to accurately center and retain the casing sections in alignment. The lowering of the casing sections into place may be accomplished by a rope or cable bridle which may be passed through upper ones of the vent passages 13 and which may be attached to the lift line of the crane or other lifting mechanism hereinbefore mentioned.

When as many casing sections have been placed one on the other to provide a chamber of the required depth, a prefabricated reinforced cover 23 is placed over the upper end of the casing to close the latter. Suitable loops 24 are provided in the cover to which bridles may be attached to place or remove the cover. Also, a plug member 27 is provided centrally of the cover which may be removed as desired to facilitate periodic inspections of the cesspool chamber. When the cover has been finally set, the waste line 28 is installed and the peripheral space around the casing is filled with coarse gravel 22 or other such porous medium after which the earth retaining dam sleeve, if any has been used, is removed and the cover fill 29 of earth is laid over the cover. This completes the installation.

In operation, the fluid waste matter entering the cesspool chamber through the waste pipe 23 will, if the level of fluid in the chamber is sufficiently high, flow outwardly and downwardly through the inclined passages and will seep through the back fill 22 into the surrounding earth. The inclination of the passages also serves to lend force to the outward flow of the fluids, thus maintaining the cesspool in a better state of clearance than might be expected of conventional construction wherein the fluids would have to find their way through the interstices between loosely laid brick or stone. It will also be seen that the erection of a cesspool constructed in accordance with the principles of my invention requires only a fraction of the time necessary to prepare for and assemble a conventional cesspool; that the resulting structure is much stronger than the usual stone or brick structure and that all of the construction operations may be carried out above ground level thus eliminating the hazards generally associated with subterranean construction work of this nature.

I claim:

1. In a cesspool structure, a casing comprising a plurality of preformed tubular cast concrete sections disposed in axially aligned relation to form inner and outer walls of a cesspool chamber, each section having axially extending notches in an end surface thereof and at least one of said sections having downwardly inclined passages extending from the chamber radially outwardly of the wall thereof, H-shaped keys insertible in said notches having portions extending radially beyond said inner and outer walls, said portions having extensions embracing the inner and outer wall portions of adjacent sections in said notches and in the end surface confronting said notches, respectively, for holding the respective sections in relative axial alignment, and a removable cover engaged with an end surface of a section for closing an end of said chamber.
2. In a cesspool structure, a casing comprising

a plurality of substantially cylindrical preformed tubular cast concrete sections disposed in axially aligned relation to form inner and outer walls of a cesspool chamber, each section having axially extending notches in an end surface thereof and at least one of said sections having downwardly inclined passages extending from the chamber radially outwardly of the wall thereof, substantially H-shaped keys insertible in said notches having portions extending radially beyond said inner and outer walls, said portions having extensions embracing the side wall portions of adjacent sections in said notches and in the end surface confronting said notches, respectively, for holding the respective sections in relative axial 15 and rotational alignment.
